UNITED STATES PATENT OFFICE

EUGENE J. RAY, OF BEVERLY, MASSACHUSETTS, ASSIGNOR TO UNITED SHOE MACHINERY CORPORATION, OF PATERSON, NEW JERSEY, A CORPORATION OF NEW JERSEY

HEEL TRIMMING AND COMPRESSING MACHINE

Application filed November 12, 1927. Serial No. 232,899.

This invention relates to improvements in machines for operating upon shoe-part blanks. While, as herein shown and described, the invention is illustrated as embodied in a machine for operating on heel-part blanks, it will be understood that in various aspects it may have other applications and uses.

Machines having mechanisms for effecting both trimming and compressing operations upon blanks such as, for example, heel blanks, as heretofore constructed, have performed these operations at a plurality of different stations, thereby necessitating the use of more or less complicated mechanism for transferring blanks from one station to another, and for properly locating the blanks with respect to the operating devices at each of the stations. It is an object of the present invention to provide an improved machine which, while retaining the advantages of machines of the type above referred to as heretofore constructed, will be more simple in construction and more certain in operation.

To this end, a feature of the invention consists in the provision, in a machine for operating upon shoe-part blanks, of a die, and a presser member operable within the die, the die and presser member being arranged for relative movement for trimming and compressing blanks operatively positioned between the die and the presser member. Accordingly, the illustrated machine is provided with a die having a mold cavity the walls of which terminate in cutting edges, a presser member movable into the die, means for feeding blanks one at a time into operative position relatively to the die and presser member, and means for causing movement of the presser member into the die to force a blank through the plane of the cutting edges of the die, thereby trimming the blank, and then to force it into the mold cavity of the die to compress the blank within the die.

Preferably, and as shown, means is provided

for ejecting from the die trimmed and compressed blanks. As illustrated, this means comprises a movable plunger forming the bottom of the die and co-operable with the presser member to compress a trimmed blank and then operative to eject a trimmed and compressed blank from the die.

Another feature of the invention resides in the provision in a machine of the type referred to of a die and blank-positioning means movable into the die for locating a blank relatively to the die together with means for withdrawing the positioning means from the blank while the blank is held in the die by frictional contact therewith after a dieing operation has been performed upon the blank. Preferably, and as shown, the positioning means consists in one or more jig pins mounted upon a presser member which is operative to force a blank into the die, the presser member with the jig pins being withdrawn from the die at the end of a dieing operation leaving the blank held within the die by reason of its frictional engagement with the walls thereof.

Other features of the invention consist in the provision of improved means for feeding blanks to mechanism for operating upon the blanks, and improved means for removing scrap material from the vicinity of the operating members.

In the drawings,

Fig. 1 is a side elevation, partly in cross-section, showing the general organization of the machine according to one embodiment of the invention;

Fig. 2 is a perspective view, partly in section, showing portions of the trimming and compressing mechanism;

Fig. 3 is a view showing the arrangement of the mechanism for controlling the blank carrier arms;

Fig. 4 is a perspective view of the combined die and mold and the presser member;

Figs. 5 and 6 are cross-sectional views illus-

trating the operation of the combined die and mold and the presser member;

Fig. 7 is a detailed view of the carrier arms;

5 Fig. 8 is a perspective view of the air-supply connections to the die; and

Fig. 9 is a detailed view illustrating the air-supply-valve operating parts.

Briefly stated, and as shown in Figs. 10 and 2, the illustrated machine is provided with a magazine 12 from which heel blanks are fed one at a time by a feed slide 14, and are moved by means of carrier arms 16 into operative position with respect to co-operating die members 18 and 20 which operate to trim and compress the blanks, after which the carrier arms 16 are effective to move the completed blank to a discharge station. The illustrated machine is particularly designed 15 for compressing and trimming substantially to final size and shape heel bases having flat tread surfaces and undercut portions, adapting them for use in connection with shoes having so-called short soles, and provided 20 with positioning surfaces formed by jig holes adapted to receive jig pins for positioning the heel bases in various operations (the illustrated heel bases being of the type set forth and claimed in application Serial No. 25 476,659, filed in the name of G. E. Warren, June 11, 1921).

The magazine 12 is a hollow member, adapted for the reception of a stack of heel blanks such as heel bases 21 mounted, by 30 means of a bent arm 22, upon a bracket 24 secured to the machine frame 26. The upper portion of the bracket forms a feed table 28 from which the magazine 12 is spaced. The feed slide 14, above referred to, is positioned 35 between the magazine 12 and the feed table 28 and acts as a support for blanks placed in the magazine. The slide 14 has a projection 30, extending through a slot 32 in the table 28, slidably mounted upon a rod 34 secured to the bracket 24, the slide being 40 reciprocal toward and away from the die members 18 and 20 along the table 28 by means of a lever 36 and link connection 38. For removing the blanks one at a time from 45 the magazine in timed relation to the operation of the carrier arms 16, the slide 14 is provided upon its upper surface with a projection 40 arranged to engage an edge portion of the lowermost blank in the magazine 50 upon advance movement of the slide 14 to the right, and to move the blank, such as blank 41, through an opening 42 (Figs. 1 and 3) in the lower forward portion of the magazine toward the die members 18 and 20. The 55 lower forward portion of the magazine 12 is provided with a gate 44 normally held in position to close the opening 42 by a spring 46, the opening 42 being of sufficient height to permit the passage of the lowermost blank only. Upon a return movement of the slide 60

a blank, which has been removed from the magazine upon the advance movement, will contact with the outer side of the gate, which holds the blanks against further rearward movement, and, as the end of the slide 14 moves underneath the magazine, the blank will drop down upon the feed table 28 into the position occupied by blank 48 (Fig. 1). In order that each blank after it drops upon the table will be retained in position to be gripped by the carrier arms, the table is provided with serrations 49 (Fig. 3) which engage the lower edges of the blanks as they drop from the slide, thereby preventing sliding of the blanks along the table.

The carrier arms 16 for feeding blanks to the die members 18 and 20, as shown in Figs. 2, 3 and 7, are pivotally mounted upon the slide 14 at 50 and 52, respectively. The rearward portions of the arms are bent inwardly 70 and are formed with intermeshing racks 54 and 56 to obtain corresponding outward or inward movements of the arms with respect to the center line of the slide. One of the arms 16 is provided with an extension 58 arranged for contact with a cam plate 60, mounted on a rock shaft 62, which operates to open the arms, a spring 64 serving normally to maintain the arms in closed position. The forward portions of the arms are 75 bent inwardly as shown at 66 (Fig. 7) and are provided with roughened jaws 68 for engaging a blank positioned between the arms. The jaws 68 are inclined inwardly so that as the spring 64 forces the jaws toward each other, they will engage with the curved back portion of the blank in such a way as to center it longitudinally and to force it back against the curved forward end portion of the slide 16. The operation of the cam 60 is such as to permit the arms to close upon a blank 48 which has dropped upon the table 28 as the carrier is retracted with the slide 14, with the jaws 68 positioned adjacent to and in front of the magazine 12. Upon the next forward movement of the slide 14 the arms 16, with a blank now gripped between them, will be moved forwardly until the blank (such as blank 70) is in position above the lower die member 20. The cam 60 is then 80 actuated to open the arms, thereby permitting the blank to drop upon the lower die member 20 in position for the trimming and compressing operations.

As previously indicated, the trimming and compressing mechanism comprises upper and lower die members 18 and 20. As shown in Figs. 4, 5, 6 and 8, the upper die member 18 which forms a combined die and mold comprises a casting 72 having a heel-shaped cavity 74 forming a heel mold. The walls of the mold project below the lower surface of the casting 72 and terminate in cutting edges 76. The casting 72 (Fig. 2) is mounted upon a stationary head 78 supported by standards 85

80 secured to the lower portion of the machine frame 26. A block or plunger 82 attached to a link 84 in the head 78 and held normally against the lower surface of the head forms a closure for one end of the heel mold.

The lower die member 20 comprises a plate 86 upon which is supported a heel-seat die, or presser member 88, in alignment with the upper die member 18, and adapted closely to fit within the mold cavity 74 of the casting 72. The upper surface of the presser member 88 is shaped to receive a heel blank (such as blank 89 in Fig. 6), positioning members comprising jig pins 90 being provided to cooperate with positioning surfaces formed by jig holes 91 in the blank to locate the blank accurately with respect to the cutting edges 76. The upper surface of the presser member 88 is formed with curved surfaces 92 and 94 for imparting the desired configuration to the heel-seat portion of the blank during the compressing operation.

The plate 86 is secured to the upper surface 25 of a cross-head 96 slidably mounted on the standards 80 and arranged for movement toward and away from the stationary head 78 by means of toggles 98 (Fig. 1). The mechanism for actuating the slide 14 is so timed 30 that, shortly after the cross-head 96 begins its upward movement, the carrier arms 16 position a blank directly above the presser member 88 with the jig holes of the blank in alignment with the jig pins 90 of the 35 presser member. As the cross-head continues its movement, the jig pins enter the jig holes of the blank and the arms 16 are actuated to release the blank which drops upon the presser member into proper position for the trimming and compressing operations as shown 40 in Fig. 6. The blank is then moved upwardly into engagement with the cutting edges 76 and is forced through the plane of the cutting edges into the mold cavity 74, the presser member 88 acting as a cutting block co-operating 45 with the edges 76 to trim the blank. Upon still further upward movement of the head 96, the presser member 88 is forced into the mold to compress the blank between the presser member and the block 82, in the manner illustrated at 97 in Figs. 1 and 5, the walls of the die preventing expansion of the blank in a lateral direction. The block 82 is provided with recesses 100 adapted to receive the 50 jig pins 90 during the compressing operation to prevent injury thereto.

After the heel blank is compressed, the cross-head 92 is lowered withdrawing the presser member 88 from the mold, the trimmed and compressed heel being held within the mold because of its frictional engagement with the side walls thereof.

In order to eject the heel from the mold the plunger block 82 is operated, through a link connection 102 and link 84 by means of a

lever 104, to force the blank downwardly out of the mold. The ejecting operation is timed to take place as the slide 14 is partially advanced into a position such that the blank will drop upon flattened extensions 105 provided at the outer ends of the carrier arms 16.

The extensions 105 are of sufficient width when the arms are closed to receive and support upon their upper surfaces a trimmed and compressed blank, such as blank 106, Fig. 1. After receiving a heel blank the carrier arms 16 are advanced still further until the extensions 105 are positioned over a discharge chute 107, the cam 60 then operating to open the arms 16 thereby dropping the completed blank into the chute.

While the preceding description has set forth the operation of the slide 14 and carrier arms 16 at different stages of the progress of a blank through the machine, it is to be understood that several different blanks are handled simultaneously. For example, as shown in Fig. 2, the slide 14 has been advanced to the right, moving the blank 41 from the magazine, the arms 16 have gripped a second blank 70 and advanced it into position over the presser member 88, and a completed heel part 106 has been received upon the extensions 105 and moved over the chute 107. Subsequently, the arms 16 are opened to drop the completed heel part 106 into the chute, and to drop the blank 70 upon the presser member 88, after which the slide and carrier are retracted, permitting the blank 41 to drop upon the table 28 into position to be grasped by the carrier arms.

To avoid contact with the die members which are approaching each other during the rearward movement of the carrier, the arms 16 are held in open position by the cam 60 during rearward movement of the slide 14.

The illustrated machine is provided with a motor 108 (Fig. 1) which through gears 110, 112 and 114 drives a gear 116, keyed to a shaft 118, and by which the various operating parts of the machine are actuated. The mechanism for reciprocating the slide 14 and carrier arms 16 comprises a link 120 pivoted at 122 to a portion of the machine frame, and carrying rod 124 connected to one end of the slide actuating lever 36. Movements of the lever 36 about its pivot 126 are produced by the rod 124 which is actuated by a roll 128, riding in a cam track 130 in the gear 116. Movements of the cross-head 92 toward and away from the head 78 in effecting operations upon blanks, are produced through the toggles 98 by means of a crank 132 eccentrically mounted upon the shaft 118.

For operating the block 82 to effect the removal of a completed blank from the mold, the lever 104 is rocked about its pivot 134 by means of a yielding connection comprising links 136 and 138, the connection being operated at the proper point in the cycle of

operations positively to move the plunger block 82 downwardly by bell-crank lever 140 which is actuated by means of a roll 142 riding in a cam track 144 formed in the gear 116.

For producing opening and closing movements of carrier arms 16, mechanism is provided for rocking the shaft 62 to which is secured the cam 60. This mechanism (Figs. 1 and 3) comprises a gear 146 driven by means of a gear 148 keyed to the shaft 118. By means of a cam 150 on the gear 146 reciprocating movements are imparted to a rod 152 mounted for sliding movement in brackets 154 and 156 (Fig. 3) forming a part of the machine frame. The rod 152 carries a block 158 making sliding contact with a plate 160 carried by a shaft 162 mounted on frame bracket 164, to rock the shaft 162 responsive to reciprocations of the rod. Such movements are transmitted to the cam shaft 62 by means of a bifurcated member 166 on the shaft 162 in engagement with a projection 168 extending from a plate 170 mounted on the end of the cam shaft 62.

In order to prevent the likelihood of scrap material accumulating in proximity to the die members and the possibility of some of such material entering the mold cavity, the die members are provided with knives 172 and 174 (Figs. 4, 5 and 6) co-operating with knife members 176 and 178 respectively to sever into a plurality of pieces scrap material trimmed from the blanks during the upward movement of the cross-head 96. The casting 72 is provided with air-blast passages 180 which extend through the walls of the die close to the cutting edges 76 and which communicate, by connections 182, with an air-supply pipe 184 controlled by a valve 186 (Figs. 1, 3 and 9) mounted upon a bracket 188 carried by the upper portion of the machine frame. The valve is operated by means of a bell-crank lever 190 pivotally mounted at 192 and having an arm 194 normally held by means of a spring 196 in the valve 186. In order to time the opening of the valve to cause the air blast to blow away any scrap which may stick to the cutting edges 76 or collect around presser member 88, the valve-controlling mechanism is actuated simultaneously with the operation of the block 82 in ejecting a completed blank. To this end the link connection 136 is provided with a latch 198 pivoted at 200 for engaging the lever 190 and operative upon upward movement of link 136 to depress the valve, thereby causing a flow of air to the passages 180. Upon continued upward movement of the link 136 the latch 198 releases the lever 190 which is returned to inoperative position by a spring 202, thus permitting the closing of the valve 186 by means of a spring, not shown. As the link 136 descends, contact of the latch 198 with the lever 188 causes the former to rotate about its

pivot, thus permitting it to pass the lever 188 without actuating the valve 186, a spring 204 being operative to return the latch to its normal position.

In the operation of the machine heel blanks are fed one at a time from the magazine 12 and are advanced successively by carrier arms 16 into position over the presser member 88. The member 88 is moved upwardly, receiving upon the jig pins 90 a blank from the carrier arms and forcing the blank through the plane of the cutting edges 76 of the member 18, thereby trimming the periphery of the blank. The member 88 is further actuated to move within the mold cavity 74 to compress the blank and then is moved downwardly, the completed blank being held in the cavity 74 by reason of frictional engagement with the side walls thereof. The plunger block 82 is then operated to eject the blank from the mold onto the forward extension 105 of the carrier arms 16 which are operated to discharge the blank into the chute 107.

Having described the invention, what I claim as new and desire to secure by Letters Patent of the United States is:—

1. In a machine for operating upon shoe-part blanks, a die, a presser member operable within the die, and means for causing relative movement between the die and presser member to effect trimming and compressing operations upon a blank in operative position between the die and presser member.

2. In a machine for operating upon shoe-part blanks, a hollow cutting die, a presser member operable within the die, and means for producing relative movement between the die and presser member so that a blank fed into operative position between the die and presser member is trimmed by the cutting edges of the die and then compressed within the die.

3. In a machine of the character described, a die having a mold cavity the walls of which terminate in cutting edges, a presser member operable within the die, means for feeding a blank into operative position between the die and presser member, and means for causing relative movement between the die and said member to force the blank past the cutting edges and to compress it within the mold cavity of the die.

4. In a machine of the class described, a die comprising walls forming a mold cavity for the reception of a trimmed shoe-part blank and terminating in cutting edges, and a presser member movable into the mold cavity to force a blank supported upon the presser member through the plane of the cutting edges of the die into the mold cavity thereby to trim and to compress the blank.

5. In a machine for operating upon shoe-part blanks, a stationary head, a reciprocating member movable toward and away from

- the head, blank-trimming means and blank-compressing means having each a part located on the head and on the reciprocating member, and means for operating the reciprocating member, the construction and arrangement being such that a blank is trimmed and compressed during a single reciprocation of said member. 5
6. In a machine for operating upon shoe-part blanks, a presser member having projecting positioning members to engage complementary positioning surfaces in a blank, a combined cutting die and mold having a chamber to receive a blank supported by the presser member, and means for moving the presser member and blank into the combined die and mold to trim and compress the blank. 10
7. In a machine for operating upon shoe-part blanks, a die member, a presser member operable within the die member, means on one of the members for locating a blank relatively to the die member, and means for causing relative movement between the members for effecting trimming and compressing operations upon a blank operatively positioned between the members. 15
8. In a machine for operating upon shoe-part blanks, a die, a presser member operable within the die, means for feeding a blank into operative position between the die and presser member, positioning means on the presser member for locating the blank relatively to the die, and means for producing relative movement between the die and presser member for trimming and compressing the blank. 20
9. In a machine of the character described, a die having a heel mold cavity the walls of which terminate in cutting edges, a presser member movable into the die, means for feeding a blank into operative position between the die and presser member, means on the presser member for locating the blank relatively to the cutting edges of the die, and means for causing relative movement of the die and presser member to force the blank past the cutting edges of the die and to compress it within the mold cavity of the die. 25
10. In a machine of the character described, a die having a heel mold cavity the walls of which terminate in cutting edges, a presser member movable into the die and co-operable therewith to trim a heel blank fed into operative position between the die and presser member, a movable block positioned within the die co-operable with the presser member to compress a trimmed blank, and means for moving the block to eject a trimmed and compressed blank. 30
11. In a machine of the character described, a die and a presser member movable relatively toward and away from each other to perform a trimming operation upon a heel blank, a plunger positioned in the die and co-operable with the presser member to compress a trimmed blank within the die and means op-35
- erative upon relative movement of the presser member away from the die to cause the plunger to eject a trimmed and compressed blank from the die. 40
12. In a machine for operating upon heel blanks, a stationary head, a movable head arranged for reciprocation toward and away from the stationary head, a die mounted upon the stationary head and having a cavity forming a heel mold the walls of which terminate in cutting edges, a presser member mounted upon the movable head and having blank-positioning surfaces thereon, a movable plunger mounted within the die, means for operating the movable head to force a blank supported upon the presser member through the plane of the cutting edges of the die thereby trimming the blank and to force the blank into the mold cavity thereby compressing the blank between the presser member and the plunger, and means for moving the plunger to eject the trimmed and compressed blank. 45
13. In a machine of the character described, a die, a positioning member for locating a blank relatively to the die and movable into the die, and means for forcing the blank into the die to effect an operation upon the blank and for withdrawing the positioning member from the blank while it is held within the die by frictional engagement therewith. 50
14. In a machine of the character described, a hollow die, a presser member, positioning members on the presser member for locating a blank relatively to the die, and means for moving the presser member into the die to effect an operation upon the blank and for removing the presser member and positioning members from engagement with the blank while the latter is held within the die by frictional engagement with the walls thereof. 55
15. In a machine for operating upon heel blanks, a die, a presser member, positioning members on the presser member for locating a blank relatively to the die, means for causing relative movement between the presser member and the die to effect a dieing-out operation upon the blank and for withdrawing the positioning members from engagement with the blank while the blank is positioned within the die, and means for ejecting the blank from the die. 60
16. In a machine for operating upon heel blanks, a die having a heel mold cavity the walls of which terminate in cutting edges, a presser member movable into the die, positioning members on the presser member for locating a blank relatively to the cutting edges of the die, and means for moving the presser member into the die to trim and compress a blank and to withdraw the presser member and the positioning members from the die leaving the trimmed and compressed blank therein. 65
17. In a machine for operating upon heel blanks, a die having a heel mold cavity the 70
- 75

walls of which terminate in cutting edges, a presser member movable into the die, positioning surfaces on the presser member for engagement with complementary positioning surfaces upon a blank for locating the blank relatively to the cutting edges of the die, and means for moving the presser member into the die to trim and compress the blank and to withdraw the presser member from the die, 10 the walls of the die being effective to retain the trimmed and compressed blank within the die while the presser member is being withdrawn therefrom.

18. In a machine for operating upon shoe-part blanks, a die, a presser member operable within the die, jig pins on the presser member for positioning a blank relatively to the die, and means for producing relative movement between the die and presser member 20 to force the blank past the cutting edges of the die and to compress it within the die.

19. In a machine of the character described, a die having a heel mold cavity the walls of which terminate in cutting edges, a presser member movable into the die and co-operable therewith to trim a heel blank fed into operative position between the die and presser member, jig pins for locating the blank relatively to the cutting edges prior to 30 the trimming operation, a movable block positioned within the die co-operable with the presser member to compress a trimmed blank, and means for moving the block to eject a trimmed and compressed blank.

35 20. In a machine for operating upon heel blanks, a die having a heel mold cavity the walls of which terminate in cutting edges, a presser member movable into the die, jig pins on the presser member for locating a blank relatively to the cutting edges of the die, means for moving the presser member into the die to trim and compress a blank and to withdraw the presser member from the die, and means for ejecting a trimmed and compressed blank from the die.

21. In a machine of the class described, die members for operating upon shoe-part blanks, a magazine, feeding mechanism comprising a feed slide for moving blanks from the magazine one at a time, and members mounted on the slide for engaging the blanks successively to move them into operative position relatively to the die members, said blank-engaging members being provided with extensions for receiving the blanks after operations performed upon them by the die members and for moving the blanks toward a discharge station.

22. In a machine of the class described, die members for operating upon shoe-part blanks, a magazine, a discharge chute, a feed slide for removing blanks one at a time from the magazine, blank-engaging members mounted upon the feed slide simultaneously to feed a blank into operative position rela-

tively to the die members and to move another blank into position over the discharge chute.

23. In a machine of the class described, dies for operating upon heel blanks, a magazine, a feed slide for supporting blanks in the magazine, means for imparting reciprocating movements to the feed slide, a member mounted on the feed slide effective upon movement of the slide in one direction to remove the bottom blank from the magazine, 75 and feed arms mounted on the slide, said arms being provided with jaws for gripping the said blank and operative to move it into operative position relatively to the dies, said arms having also extensions for engaging 80 the blank after it has been operated upon by the dies and operative to move the blank toward a discharge station.

24. In a machine of the class described, co-operating die members for trimming and compressing heel blanks at a single station, a magazine for the blanks, a feed slide mounted for reciprocating movement between the magazine and the die members, the feed slide having a member adapted upon advance 90 movement of the slide to force a blank from the magazine, arms mounted upon the slide for gripping such blank and operative upon the next succeeding advance movement of the slide to move it into operative position 95 relatively to the die members, and extensions upon the arms for receiving a blank after a trimming and compressing operation and for moving it toward a discharge station.

25. In a machine of the character described, 100 co-operating die members for operating upon shoe-part blanks, one of said members having an air passage extending therethrough, means for supplying an air blast to said passage to insure the removal from the vicinity of said die members of scrap material resulting from operations of the members, and a valve operatively connected to moving parts of the machine for controlling the air passage.

26. In a machine of the character described, 110 co-operating die members for operating upon shoe-part blanks, means associated with said members for severing scrap material trimmed from the blanks, one of said members having an air passage extending therethrough, and means for supplying an air blast to said passage to insure the removal of the scrap material from the vicinity of the said die member.

27. In a machine of the character described, co-operating die members for trimming and compressing heel blanks, means associated with said members for severing scrap material trimmed from the blanks, one of said members having an air passage extending therethrough, means for stripping blanks from the die members after operations upon the blanks, and means for causing a blast 125 of air through said passage to remove the 130

scrap material simultaneously with the operation of the stripping means.

28. In a machine for operating upon shoe-part blanks, a hollow die having a wall terminating in a cutting edge, the wall being provided with a passage adjacent to said cutting edge, and means for supplying a blast of air to said passage to prevent the accumulation of scrap material in proximity to the cutting edge.

In testimony whereof I have signed my name to this specification.

EUGENE J. RAY.
